GUN TESTER

Otis J. McCullough, Houston, Tex., assignor to
 McCullough Tool Company, Los Angeles,
 Calif., a corporation of Nevada

Application April 30, 1940, Serial No. 332,470

7 Claims.

My invention relates in general to the art of producing oil from the earth and relates in particular to an apparatus whereby consecutive or selected strata traversed by a bore hole may be tested to determine whether the same has producible fluids, for example, gas and oil, therein.

It is an object of my present invention to provide an apparatus whereby the perforating device may be operated to produce perforations connecting the adjacent formation with the interior of the well and a test may be immediately thereafter performed to determine whether the formation penetrated contains oil, thereby avoiding the lapse of time above referred to between the operation of the perforating gun and the reduction of the pressure in the well.

It is an object of the invention to provide an apparatus by which perforations may be first made at a selected level in the well and immediately thereafter the pressure within the well adjacent the formations may be reduced so as to cause an inflow into the well of such fluids as exist in the adjacent formation.

A further object of the invention is to provide an apparatus whereby the perforations are made and immediately thereafter the pressure within the well adjacent the perforations is reduced, without taking the pressure of mud or other liquid from the well as a whole, this feature of the invention constituting a definite safety factor in minimizing the possibility of the well blowing in out of control where the formation encountered exists under high pressure.

It is a further object of the invention to provide a device which may be moved in a well to a desired position of operation, perforations made through the wall of the casing and a sample drawn from the adjacent formation without removal of the device from the well.

A further object of the invention is to provide a means in conjunction with the device referred to in the preceding paragraph for sealing off the well adjacent the perforations so that the perforations will be relieved from the pressure of mud or other liquid contained in that portion of the well thereabove.

It is a further object of the invention to provide a combined perforating and testing device adapted to establish communication between the top of the well and the zone within the well in which the perforations have been made, thereby relieving or reducing pressure in this zone so as to induce entry of fluid from the formation into the well, and if desired to produce a flow of such

fluid through the device to the top of the well so that the character of such fluid may be observed before the device is removed from the well.

It is an object of the invention to provide a perforating and testing device for use in a well having therein a space to receive a sample, and having means for producing a pressure differential between this space and the formation which has been opened by the perforations, so as to produce a flow of fluid from the formation to the sample receiving space of the device.

Further objects of the invention are to provide a combined perforating and testing device having a tube which is moved in the well to a desired position, this tube having a perforating gun connected thereto, to provide the tube with means for opening the lower portion of the same to communication with the interior of the well for the purpose of taking a sample, to provide a means for sealing off the well adjacent the opening of the tube, to provide a device of this character through which circulation may be maintained, and to provide simple and effective means whereby control and operation of the cooperating parts of the device are accomplished.

Further objects and advantages of the invention will be brought out in the following part of the specification.

Referring to the drawings which are for illustrative purposes only:

Fig. 1 is a partly sectioned view showing a preferred embodiment of my invention in a well casing.

Fig. 2 is an enlarged fragmentary sectional view showing the upper part of the device prior to the actuation thereof.

Fig. 3 is an enlarged sectional view showing the lower portion of the device prior to its actuation.

Fig. 4 is an enlarged sectional view similar to Fig. 2 but showing the device with its packer set or expanded in the casing.

Fig. 5 is a sectional view showing the lower portion of the device after setting of the packing and the opening of the sample receiving means so as to receive a sample.

Fig. 6 is an enlarged cross-section taken on a plane represented by the line 6-6 of Fig. 3.

Indicative of the general use of my invention I have in Fig. 1 shown a well casing 10 extended in a bore hole 11 of a well so as to traverse formations 12, 13, and 14. My combined perforating and testing device 15 comprises suspension means shown in the form of a tube 16 and an organization 17 consisting of a perforating

device, shown as a gun 18, packing means 19, and closure means 20 adapted to be actuated so as to establish communication between a sample receiving space within the device and the zone in the well in which the perforations have been made.

As best shown in Figs. 2 and 3, the organization 17 includes an upper member 21 having threaded connection at 22 with the lower end of the tube 16. The member 21 has an axial opening 23 threaded at 24 to receive the upper end of an inner tube 25 which extends down through the packing means 19 and, as shown in Fig. 3, has threads 26 at its lower end for connection to the closure member 20, this closure member being of annular form and having threads 27 at its lower end for connection to the upper part of the gun 18. Accordingly, by use of the tube 25 the gun 18 is connected directly through the fitting or upper member 21 with the lower end of the tube 16 which comprises a string of pipe sections joined by threaded couplings, as shown in Fig. 1, having a collar 29 at the upper end thereof for engagement of suitable hoisting equipment represented by an elevator 30.

The packing means 19 is slidably disposed on the tube 25 for the purpose of permitting a downward movement of the tube 25 through the packing means 19 after the packing means has been set in the casing 10, thereby moving the closure member 20 from the position in which it is shown in Fig. 3 downward and away from the bushing 31 which forms the lower end of the packing means 19, as shown in Fig. 5. When the tube 25 and the gun 18 are lowered relative to the packing device 19, as shown in Fig. 5, openings 32 in the tube 25 will be exposed below the bushing 31, thereby establishing communication between the interior of the tube 25 and the space within the casing 10 below the packing means 19.

As shown in Figs. 2 and 3, the packing means 19 has a cylindric shell 33 threaded to and extending upwardly from the bushing 31. At the upper end of this shell 33 threads 34 are provided to connect it to a body 35 having upwardly diverging guides 36 for slips or jaws 37 which normally rest in lowered position, as shown in Fig. 2. The upper cylindric portion 38 of the slip supporting body 35 is threaded to receive a collar 39 having an inwardly turned lip 40. The lower flange 41 of a sleeve 42 rests within the collar 39, and the sleeve 42 projects upwardly from the collar so as to support thereon a packing element shown as consisting of a plurality of rubber rings 43. A collar 44 is threaded on to the upper end of the sleeve 42 and a cylinder section 45 is threaded on to the upper portion of the collar 44 so as to cover the space 46 between the seat 47 at the upper end of the collar 44 and the rounded lower face 47' of the member 21 which threads on to the upper end of the tube 25. The member 45 has slots 48 therein and the cylindric portion 38 of the slip supporting body 35 has slots 49 so that during the time the device is being moved axially in the well, with the member 21 in raised relation to the seat 47 of the collar 44, circulation of mud may occur through the space 50 within the sleeve 42, thereby bypassing the packing rings 43.

As shown at the lower end of Fig. 2 and at the upper end of Fig. 3, the jaws 37 are connected by links 51 to a ring 52 which surrounds the upper portion of the cylindric shell 33 and by swivel connecting means 53 is connected for rel-

ative rotation to the upper end of a sleeve 54, having controlled rotative and sliding movement on the shell 33, and having means for frictional engagement with the wall of the casing 10, such means being shown as bow springs 55.

5 The sleeve 54 has bayonet slots 56 therein, engaged by the heads 57 of screws which are threaded into the shell 33. When the screw heads 57 are in the upper portions of the bayonet slots 56, as shown in Figs. 1 and 3, the sleeve 10 54 will be in lowered position on the shell 33 and the links 51 will hold the jaws 37 in lowered position on the guides 36 so that the device may be readily moved in the well.

15 The perforating gun 18 is of the type shown in the copending application of Ira J. McCullough for Gun perforator, Serial No. 258,606, now Patent No. 2,218,802, granted October 22, 1940, and also Patent No. 2,154,859. Such gun has a plurality of barrels 58 in which projectiles 20 are held with associated powder charges whereby the outward propulsion of the projectiles may be obtained. To ignite the powder charges, a priming device or igniter 59 is supported in position below a firing pin 60 which extends

25 downward from a head 61 mounted in an axial opening 62 in the upper part of the gun assembly, and has threaded adjusting means 63 on the head 61. A tube 64, closed at its lower end, rests upon the head 61 and extends upward through 30 the tube 25 and has on the threaded upper end 65 thereof which projects from the upper end of the tube 25, a head 66 having limited axial movement in the opening 23 of the member 21 and having a downwardly faced sealing cup ring 67 thereon. The lower portion of the tubular member 64 has a plurality of small openings 68 through the wall thereof and the head 66 at the upper end of the tubular member 64 has therethrough an axial flow controlling orifice 69.

35 The threads 70 by which the member 20 is connected to the member 31 are preferably right-hand and are of such character that the 40 joint formed thereby may be readily unscrewed. So that there may be but little binding of the threads when the parts 20 and 31 are connected as shown in Figs. 1 and 3, it is preferable to provide shoulders as shown at 10 in Fig. 1, between these parts 20 and 31 to serve as a stop to limit the distance the member 20 may be screwed into the member 31.

45 When the members 20 and 31 are in threaded engagement, the openings 32 will be closed by a 50 valve means consisting, as shown in Figs. 2 and 3, of a sleeve 71 having an internal shoulder 72 at its upper end against which an annular body of packing 73 is held by a lantern ring 74 as shown in Fig. 2. Below the ring 74, as shown in Fig. 3, 55 a body of packing 75 is held by a bushing 76 which threads into the lower end of the sleeve 71. The packing 73 and 75 provides means for frictional engagement with the outer surface of the tube 25 and prevents leakage of fluid through the 60 interior of the sleeve 71 to the openings 32.

65 The operation of the device embraces a method including the following steps, which are given in their preferred order, although it will be evident to those familiar with the invention that this 70 order of steps need not be preserved. Assembled as shown in Figs. 1, 2, and 3, the device 15 is lowered into the well by means of the tube 16, to bring the gun 18 to a desired or selected position. The gun 18 may be then fired by dropping a 75 go-devil down through the tube 16 so that the

same will strike the head 66 at the upper end of the tubular member 64, so that the firing pin 60 will be driven down into firing engagement with the primer 59. The go-devil 80 is shown resting against the upper end of the head 66 in Fig. 4. The tube 16 may be then rotated so as to rotate the device 15 relative to the sleeve 54 so as to bring the screw heads 57 into alignment with the vertical portions 81 of the bayonet slot 56; whereupon the tube 16 may be lowered so that the body of the device 19 will move downward relative to the slips or jaws 37 which are at this time held stationary by reason of their support through links 51 on the sleeve 54 carrying the bow springs 55 which engage the casing 10. The upwardly diverging tracks 36 will, by downward movement, wedge the slips 37 tightly outward against the casing 10, to rigidly secure the device 19 at a desired position in the casing 10. A lifting force will be now applied to the tubing 16 so that the weight of the tubing 16, the tube 25 and the perforating gun 18 will be taken off of the threads 70. With the threads 70 now released from friction, right-hand rotation may be applied through the tubing 16 to unscrew the member 20 from the bushing 31. The tubing 16 may be then lowered so that the member 21 at the upper end of the device 17 may move down from the position in which it is shown in Fig. 2 within the cylindrical guard member 45 to engage the seat 47 provided at the upper end of the member 44, which member 44 will now be forced downward against the assembly of packing rings, to expand the packing rings into engagement with the casing 10 as shown in Fig. 4. This downward movement of parts will carry the tube 25 downward so as to move the inlet openings 32 downward from their position of Fig. 3 out through the closure means comprising the sleeve 71, to the position thereof shown in Fig. 5, below the lower end of the bushing 31.

The engagement of the lower face 47' of the member 21 with the seat 47 closes the bypass opening 50 through the packer 19, so that the fluid above the packer in the well will be supported thereon. That portion of the interior of the casing 10 below the packer 19 will be connected to the sample receiving space of the device through the openings 32. The sample receiving space of the device includes the interior of the tubular member 64 having entrance openings 68 therein, and also includes the interior of the tubing 16 to which piping may be connected by means of the coupling 29 at the upper end thereof. The interior of the tubing and of the tubular member 64 thus opened to communication with that portion of the well below the actuated packer 19 is at a lower pressure than the well pressure at the level of the device 17, whereby a pressure differential is produced which will cause an inflow of fluid through perforations 85 which have been made in the casing 10 into the sample receiving space of the combined testing and perforating device. If the formation adjacent the perforations carries fluids under pressure, for example, oil and gas, such fluids in many instances will pass up through the tubing 16 to the top of the well. In other instances the sample taken through the perforations 85 may pass only a relatively short distance up into the tubing 16, wherein the sample is trapped by the mere expedient of applying a lifting force through the tubing 16 to move the openings 32 of the member 25 up into the sealing member comprising the sleeve 71, or in other words substantially into the

position thereof shown in Fig. 3. Further lifting force applied through the tubing 16 will raise the body 35 relative to the slips 37, thereby releasing the slips, and at this time the member 21 will be raised into approximately its relative position of Fig. 2 so that weight will be taken off of the packing rings 43, thereby releasing the packer so that the entire assembly may be removed from the well.

10 In the preferred practice of the invention the organization 17 is lifted about 20 feet after the gun 18 is fired so as to be out of the way of sand which may enter the casing through the perforations when the pressure is released as described in the foregoing. Also, after the making of the test and prior to the lifting of the device from the well, the member 20 may be screwed several turns into the member 31 to lock the parts in closed relation.

20 I claim as my invention:

1. In a perforator and tester for use in a well, the combination of: a tube adapted to be moved in a well to a desired position of operation, said tube having means near the lower end thereof to provide an inlet opening for said tube; a perforating gun connected to the lower end of said tube; a member movable on the lower portion of said tube, said member having means to close said opening when it is in one position on said tube and to open said opening when it is moved to another position on said tube; means engageable with the wall of the well to control said member whereby relative movement of said member and said tube to open said inlet opening may be accomplished; and means for firing said gun so as to discharge a projectile to form a perforation to connect the interior of the well with the adjacent formation whereby fluid may flow into said well and said tube.

40 2. In a perforator and tester for use in a well, the combination of: a tube adapted to be moved in a well to a desired position of operation; valve means at the lower end of said tube; a perforating means carried by the lower end of said tube; a member in limited axial sliding relation to the lower end of said tube; means operative to lock said member to the casing in the well whereby said tube may be then moved axially relative to said member; means carried by said member to open said valve means when said tube is moved axially relative to said member; and means for actuating said perforating means.

3. In a perforator and tester for use in a well, the combination of: a tube adapted to be moved in a well to a desired position of operation; valve means at the lower end of said tube; perforating means carried by the lower end of said tube; a member in limited axial sliding relation to the lower end of said tube; means operative to lock said member to the casing in the well whereby said tube may be then moved axially relative to said member; means carried by said member to open said valve means when said tube is moved axially relative to said member; means for actuating said perforating means; and means carried by said member to seal off the well above the lower end of said member.

4. In a perforator and tester for use in a well, the combination of: a tube adapted to be moved in a well to a desired position of operation; valve means at the lower end of said tube; perforating means carried by the lower end of said tube; a member in limited axial sliding relation to the lower end of said tube; means

operative to lock said member to the casing in the well whereby said tube may be then moved axially relative to said member; means carried by said member to open said valve means when said tube is moved axially relative to said member; means for actuating said perforating means; and a packer connected to said member actuated in response to said relative axial movement of said tube and said member.

5. In a perforator and tester for use in a well, the combination of: a sample taking member adapted to be moved in a well to a desired position of operation, said member comprising an inner part having a closure element connected to the lower portion thereof and a tubular shell connected to said closure element and extending upwardly therefrom around said inner part, there being means operating in response to rotation of said inner part relative to said shell to disengage said closure element from said shell; suspension means extending upward from said inner part; means on said shell operative to lock the same stationary in the well; packing means on said shell to seal off the well above the lower end of said shell; and a perforating gun connected to said inner part and extending below said closure element.

6. In a perforator and tester for use in a well, the combination of: a tube adapted to be moved in a well to a desired position of operation, said

tube having a laterally directed inlet opening near the lower end thereof; a perforating gun connected to the lower end of said tube; a member movable on the lower portion of said tube; means on said member engageable with the wall of the well to hold said member whereby movement of said tube relative to said member may be accomplished; a slide valve element engaging an external portion of said tube and movable to open and close said inlet opening, said element being operatively connected to said member; and means for firing said gun to discharge a projectile to form a perforation to connect the interior of the well with the adjacent formation whereby fluid may flow into said well and said tube.

10 7. In a perforator and tester for use in a well, the combination of: a tube connected to the lower end of a string of pipe, said tube having inlet valve means; a perforating gun connected to the lower end of said tube, said gun having a firing pin projecting from the upper end thereof; a firing pin extension extending up through said tube to a point contiguous to the upper end of said tube; means movable through said string of pipe to apply a downward force to said firing pin extension; and means for actuating said inlet valve means of said tube.

OTIS J. McCULLOUGH.
